UNITED STATES PATENT OFFICE.

WILHELM SCHURR, OF LANGNAU-ON-THE-ALBIS, SWITZERLAND.

ATHLETIC EXERCISER.

1,353,938.

Specification of Letters Patent. Patented Sept. 28, 1920.

Application filed June 2, 1919. Serial No. 301,291.

To all whom it may concern:

Be it known that I, WILHELM SCHURR, a Swiss confederate, residing at Langnau-on-the-Albis, Canton Zürich, Switzerland, have invented new and useful Improvements in Athletic Exercisers, of which the following is a specification.

This invention relates to athletic exercisers for strengthening the muscles of hands and 10 arms.

Among existing devices of this kind there are provided elastic or spring-controlled contrivances which produce the desired effect less on account of their weight than 15 through the effort the hand is put to in repeatedly compressing elastic parts so as to react on the muscles of the arm. These devices have generally been constructed of metal parts fitted together, whereby they are 20 necessarily rendered comparatively expensive especially those composed of castings and springs.

The object of my invention is to provide a springy or elastic dumb-bell or athletic 25 exerciser, for the hands and arms, and which is made of a single piece of wood or other convenient material suitably slotted to form three combined elastic parts, strips or languettes.

To render the invention clear, I will describe the same fully with reference to the accompanying drawing which shows a perspective face view of a suitable form by way 30 of example only.

In a flat piece of wood or other material

1 I produce or cut, from opposite ends 2, slots such as 3 which advantageously are slightly curved as shown or of any other configuration and which leave an intermediate strip or bridge 4 and external 40 prongs 5. Naturally it is preferable though not absolutely imperative to make this device in a single piece. The parts 4 and 5 are thus rendered elastic so as to possess more or less spring force or resistance. 45

For practising with this exerciser, the device is taken edgewise in the hand and the prongs 5 are then compressed whereby the spring force both of the prongs 5 as also that of the bridge 4 has to be overcome. 50

My improved exerciser is very simple to make and carry out, and it is extremely cheap when made of wood.

It can be produced in different sizes so as to suit adults and children or young people 55 by suitably determining the cross-section of the prongs 5 and bridge 4. The form of this exerciser may be altered to suit various requirements without departing from the spirit of the invention. 60

Having thus described my invention, what I claim is:

An elastic athletic exerciser made of a single piece of oblong wood, a shoulder at each end thereof, a longitudinal prong extending from each shoulder in opposite directions, and a longitudinal elastic bridge uniting said shoulders. 65

WILHELM SCHURR.
